B. Singen Atty.

UNITED STATES PATENT OFFICE.

EDWIN DANIEL BERRY, OF PALMERSTON NORTH, NEW ZEALAND

REISSUED

COOLER FOR CREAM AND OTHER LIQUIDS.

Application filed November 7, 1924, Serial No. 748,471, and in New Zealand February 16, 1924.

This invention relates to a new and improved construction of cooler, employing humid ammonia gas as the cooling medium, that has been devised specially for use in 5 dairy factories and like places for the cooling of cream after Pasteurization. The construction devised is however suitable for the treatment of other liquids and also for the employment of other fluid cooling agents 10 than the ammonia gas referred to.

In this invention provision is made for the cream or other liquid, while passing through the cooler, being entirely enclosed so that it cannot be affected by surrounding 15 atmospheric conditions, as is the case with the surface coolers generally used in similar circumstances. It is generally conceded that cream while cooling becomes absorbent to the surrounding air conditions and as these 20 sometimes are charged with fumes or odours that are deleterious to the cream, the cream is liable to be affected thereby. With this invention in use therefore, this liability is removed.

25 Provision is also made in the construction of the cooler, for the cream and the cooling medium flowing side by side throughout a continuous zigzag course and in the same direction, so that the cream at its highest 30 temperature comes under the influence of the cooling medium at its lowest temperature, and thus especially in the case of ammonia gas as the cooling medium, any liability of freezing taking place to check the 35 flow is obviated, and moreover the cooling operation carried on right throughout the course of the liquid.

The invention consists in a special construction of appliance whereby these 40 results are obtained and embodies special details of construction by the employment of which important advantages in the working and general care and oversight of the cooler, are obtained.

45 These general features and details of construction are shown in the accompanying drawings and will be hereinafter fully explained in relation thereto.

In such drawings:—

50 Figure 1 is an end elevation of the cooler.

Figure 2 is a side elevation thereof showing portion of an insulated casing broken away.

55 Figure 3 is an enlarged sectional elevation showing the manner of forming the

joint between two of the tubular elements of the cooler.

The cooler as made in accordance with this invention is formed by a number of jacketed tubular elements arranged to extend in parallel lines one above the other between vertical end frames or standards A, each of such elements being formed by an internal tube B and an outer jacket tube C. The ends of the internal tubes B of each 60 element are carried out through the respective end frames A and the adjacent ends are then connected together by semicircular unions D so arranged relatively at both ends of the cooler that a continuous zig-zag passage is obtained from one end of the bottom tube B throughout all of the tubes in turn 65 to the end of the top tube. Each end is fitted to connect with pipes through which the cream supply is led into the bottom tube and is carried away from the top tube, the flow through the series being maintained 70 by pumping or other desired power.

75 Each jacket tube C, at each end of the element is closed in around the tube B by drawing or otherwise, and the several jacket tubes of the series are connected together 80 by unions E obtained by welding or otherwise, disposed near their ends so that one continuous zigzag course is obtained from 85 the end of the lowest jacket corresponding to the inlet end of the lowest tube B, through all of the jackets in turn, to the end of the topmost jacket corresponding to the outlet 90 end of the highest tube B.

95 An inlet nozzle F is provided in the end of the bottom element jacket through which the ammonia supply is led, and an outlet G of the required larger diameter leads from the end of the top element jacket, and in practice may be fitted with a pressure gauge.

Thus the cream to be cooled may be sent along within the tubes B while the cooling medium is caused to travel in the same direction within the surrounding jackets, in 100 order to cool the cream to the required degree.

Each element is bent upwards in a slight curve from both ends to its middle so that any moisture left within the tubes will 105 drain towards the ends. This is particularly of advantage with the inner cream tubes B as preventing the accumulation of matter therein and facilitating the cleaning of the tubes with hot water and the drain- 110

ing away of any residue. The end to end bending of the elements will also provide for the expansion and contraction of the tubes brought about by the conditions governing the use of the cooler, without affecting the joints with which the tubes B are connected to the end frames A. The inner tube B is also preferably given less arch from end to end than the outer jacket in order that it may bend upwards to a greater extent and still leave a clear annular space between the tube and the jacket.

The unions D are so secured in position to connect the respective ends of the tubes B that they may be readily removed and replaced whenever required. When these unions are removed the tubes B are left open from end to end, so that cleansing appliances may be pushed or drawn through them. The manner of forming the ends of the tubes and the union joints is shown in the detail Figure 3. Each tube B at its extremity is turned out over the drawn in end of the jacket tube C, so that a socket end C' is formed. The union D at each end of the semi-circular passage through it, is formed with a shoulder D' that is made to enter the socket end of the tube C, such end then engaging a shoulder D² formed around the first mentioned shoulder. A suitable rubber or like packing washer H is arranged upon this shoulder. On each side of the union a flange J is formed to project laterally outward such flange having a slot J' extending in from its edge. On the outer side of the frame A a number of bolts K are hinged so that two are provided for each union, one on each side thereof. Each bolt is designed to be turned out to enter the slot J' of the corresponding flange J and is provided with a wing nut screwed on to its end, which by engaging the flange on the edges of the slot, will cause the union to be forced in hard upon the ends of the tubes B with a rubber washer between to make the required liquid

tight joints therewith. When the nuts are loosened, the bolts may be turned out to free the union so that the union may then be removed.

The appliance thus made will have its sides covered in by casing plates M extending between the end frames A and the space between packed with any approved insulating medium that will serve to conserve the cooling effect of the cooling medium upon the cream.

I claim:

1. A cooler of the class described, comprising end frames, inner tubes connecting said end frames and extending through openings therein, jacket tubes each associated with one of said inner tubes and of greater diameter than said inner tubes, said jacket tubes having diametrically reduced ends fitted around said inner tubes, said inner tubes having reversely folded ends extending around and fitted on the ends of the jacket tubes, unions connecting the inner tubes in pairs and connections between the jacket tubes.

2. A cooler of the class described, comprising end frames, inner tubes connecting said end frames and extending through openings therein, jacket tubes each associated with one of said inner tubes and of greater diameter than said inner tubes, said jacket tubes having diametrically reduced ends fitted around said inner tubes, said inner tubes having reversely folded ends extending around and fitted on the ends of the jacket tubes, unions connecting the inner tubes in pairs, said unions having shouldered ends fitted in the ends of said inner tubes and packing washers on said shouldered ends of said unions and between the same and the reversely folded ends of the inner tubes.

In testimony whereof, I affix my signature.

EDWIN DANIEL BERRY.
